CHARLES R. BUTLER, OF LONG BEACH, CALIFORNIA

INTERNAL-CASING WRENCH

Application filed June 28, 1927. Serial No. 201,995.

My invention relates to oil well equipment, and it relates particularly to a novel casing wrench. In producing an oil well the well is drilled to the oil-bearing sands and a well 5 casing is set in place. The oil-bearing sands are then penetrated and an oil string is set in the well. The lower end of the oil string has a screen pipe which sets firmly at the bottom of the hole. A casing head is attached 10 to the upper end of the oil string. Almost always the upper end of the oil string when it has been set in the well is too high for a proper positioning of the casing head. It is, under these conditions, necessary to remove 15 the top pipe of the oil string and to replace it by a shorter one. When making this replacement, it is desirable to hold the oil string from rotation immediately below the top pipe so that the top joint will be broken.

20 It is an object of this invention to provide an internal casing wrench which may be inserted into the oil string and caused to grip it so that the oil string below a certain point cannot rotate.

25 Another object of the invention is to provide a casing wrench of this character which may be moved into the casing to a proper position and then set to grip the casing.

It is a still further object of the invention 30 to provide a casing wrench of the character mentioned in which the torque applied to the casing being unscrewed causes the wrench to grip the casing.

Other objects and advantages will be made 35 evident hereinafter.

Referring to the accompanying drawings in which I illustrate a preferred embodiment of the invention:

Fig. 1 is a diagrammatic view illustrating 40 its utility.

Fig. 2 is an elevational view showing the invention on an enlarged scale, the invention being in non-gripping position.

Fig. 3 is a view similar to Fig. 2 but showing 45 the wrench in gripping position.

Fig. 4 is an elevational view of Fig. 2.

Fig. 5 is a bottom plan view taken as indicated by the line 5—5 of Fig. 2.

Fig. 6 is a cross-section taken on the line 50 6—6 of Fig. 3.

Fig. 7 is a cross-section taken on the line 7—7 of Fig. 2.

Referring particularly to Fig. 1 of the drawings, the numeral 11 represents a well casing which has been installed in a well, 55 and the numeral 12 represents an oil string. The upper pipe 13 of the oil string is so long that the upper end thereof projects a considerable distance above the floor of the derrick 14. The casing wrench 16 of this invention is inserted into the oil string so that the oil string may be gripped below the coupling 17 which connects the top pipe to the remainder of the string.

Referring to the other figures of the drawings the details of the invention will be described. The invention provides a primary member in the form of a body 20 and a secondary member in the form of a sleeve 21. The body 20 has an upper threaded end 23, 60 by means of which it may be connected by a coupling 24 to a column 25. The upper end of this column 25, as illustrated in Fig. 1, projects above the upper end of the top pipe 13 and may have a wrench 26 applied thereto 65 so that the body 20 may be restrained from rotation. The body 20 has a cylindrical portion 28 which is a sliding fit with an internal cylindrical face 29 of the sleeve 21. The lower end of the body 20 is in the form of a stem 30 which is considerably smaller than the other part of the body 20 and projects through a lower cylindrical opening 31 of the sleeve 21. At the extreme lower end of the stem 30 is a collar 32 which prevents the 70 sleeve from dropping from the body 20. Formed on the body 20 between the cylindrical portion 28 and the stem 30 is an operating means in the form of a cam 34 which provides cam faces 35. These cam faces 75 are tangential to a circle generated around the axis of the body 20 and taper outward as the upper end of the body is approached. The cam 34 is provided with vertical edges 35a, which are a greater distance from the 80 central axis of the body 20 than the cam faces 35 are. These vertical edges 35a comprise the tightening means of the invention.

The sleeve 21 is provided with openings 85 36 which carry gripping means in the form 90 of gripping means in the form 95 of gripping means in the form 100

of jaws 37, these jaws 37 being movable radially outward in a horizontal direction. The outer ends of the jaws 37 are provided with serrations or teeth 38. The jaws are yieldably retained in retracted position, as shown in Fig. 2, by retractors in the form of springs 40. These springs 40 are projected upward to the interior of the sleeve 21 through openings 41. The lower ends of the springs 40 have threaded portions 42 and have nuts 43 whereby they may be screwed in place. The lower end of the sleeve has protector lugs 44 which prevent the upper face of the collar 32 from engaging the nuts 43. The upper ends of the springs 40 extend into sockets 46 in the lower surface of jaws 37. Similar sockets 46^a are provided in the upper surface of the jaws 37, so that the latter may be reversed. The inner ends of the jaws 37 have oppositely disposed diagonal faces 48 which are adapted to be engaged by the cam faces 35 of the cam 34.

When the wrench is lowered into the casing 13 the body and sleeve or the primary and secondary members are locked from axial movement, in the position shown in Fig. 2. This locking is accomplished by releasable means in the form of a projection or key 51 which is carried by the upper end of the body 20. This key 51 is adapted to engage a countersunk shoulder 52 formed in the upper end of the sleeve 21. Connected to the upper end of the sleeve 21 at one end of the shoulder 52 is an axial slot 53. When the casing wrench has been lowered to the proper position the body 20 may be rotated in a direction indicated by the arrow 54 of Fig. 7 so that the key 51 will be removed from dotted position 55, in which position it engages the shoulder 52, into alignment with the slot 53 as shown in Figs. 2, 3, and 7. This releases the locking between the body and sleeve which will permit a relative axial movement between the two members. The sleeve 21 is provided with friction springs 57 which may be considered a part of the secondary member which are adapted to frictionally engage the inner face of the oil string or casing so that when the body 20 is rotated, the sleeve 21 will not rotate and a relative rotational movement will occur between these two parts. After alignment is procured between the projection 51 and the slot 53 the body 20 may be lowered or moved axially relative to the sleeve 21, the sleeve 21 being held stationary by the friction springs 57.

When the body 20 moves downward the cam 34 moves downward therewith and the cam faces 35 engage the faces 48 of the jaws 37, moving them outward from the position shown in Fig. 2 into the position shown in Fig. 3 so that the teeth 38 thereof engage the inner face of the oil string. The resulting outward force of the cam 34 against the jaws 37 is sufficient to provide a comparatively

firm engagement between the jaws and the oil string.

After the casing wrench has been set, as just described, the tongs 26 are applied to the upper end of the column 25 and attached to the derrick so that the column and body cannot rotate. A second tong designated by the numeral 60 is applied to the top pipe 13, and the top pipe 13 is rotated in a direction to unscrew it. When the top pipe 13 is initially rotated, the pipe immediately below it tends to rotate and moves the jaws 37 and the sleeve 21 in a rotative direction. Upon an inspection of Fig. 7 it will be seen that the slot 53 is somewhat wider than the projection 51 so that a relative rotation between the body and sleeve is possible. The action which takes place at this time is illustrated in Fig. 6. Referring to this figure the sleeve and jaws rotate around the body 20 and the cam 34, from full line positions in Fig. 6 into dotted line positions in 61, so that the vertical edges 35^a of the cam faces 35 move toward the faces 48 of the jaws. Since the vertical edges 35^a of the cam faces 35 are on a greater radius than the central parts of the cam faces, the jaws 37 will be forced outward a little more as illustrated in Fig. 6, so that an extremely firm engagement will be had between the jaws and the oil string. The wall 53^a of the vertical slot 53 limits the relative motion between the primary and secondary members, since the key 51 will come into engagement with this wall 53^a. This is a desirable feature by reason of the fact that it limits the outward movement which can be imparted to the jaws 37 and thus prevents the casing 12 from being pierced. The wall 53^a constitutes the limiting means of the invention. After this relative movement has taken place, the oil string below the coupling 17 cannot rotate, and the joint at the collar 17 will be broken and the top pipe 13 unscrewed. This top pipe 13 is then replaced by a shorter pipe which terminates at the floor of the derrick so that a casing head which is applied later may be in a proper position.

I claim as my invention:

1. An internal casing wrench comprising: a primary member, having a cam; means for moving said primary member into a casing and for holding same stationary; a secondary member carried by said primary member, said secondary member being movable in an axial direction on said primary member; a projection formed on one of said members adapted to engage a shoulder of the other of said members for restraining said members from relative axial movement, one of said members having a slot with which said projection may be aligned to permit a relative axial movement between said members, said slot being wider than said projection so that said members may rotate relatively after said

relative axial movement occurs; and jaws carried by said secondary member, said jaws being engaged by said cam and moved into engagement with said casing when a relative axial movement between said primary and secondary members occurs, said jaws being moved into tighter engagement with said casing by said cam when a relative rotative movement occurs between said primary and secondary members.

2. An internal casing wrench comprising: a primary member, having a cam; means for moving said primary member into a casing and for holding same stationary; a secondary member carried by said primary member, said secondary member being movable in an axial direction on said primary member; a projection formed on one of said members adapted to engage a shoulder of the other of said members for restraining said members from relative axial movement, one of said members having a slot with which said projection may be aligned to permit a relative axial movement between said members, said slot being wider than said projection so that said members may rotate relatively after said relative axial movement occurs; jaws carried by said secondary member, said jaws being engaged by said cam and moved into engagement with said casing when a relative axial movement between said primary and secondary members occurs, said jaws being moved into tighter engagement with said casing by said cam when a relative rotative movement occurs between said primary and secondary members; and means yieldably holding said jaws in retracted position.

3. An internal casing wrench comprising: a primary member, having a cam; means for moving said primary member into a casing and for holding same stationary; a secondary member carried by said primary member, said secondary member being movable in an axial direction on said primary member; means for releasably restraining said primary and secondary members from relative axial movement; jaws carried by said secondary member, said jaws being engaged by said cam and moved into engagement with said casing when a relative axial movement between said primary and secondary members occurs; and means carried by said secondary member for engaging said casing and frictionally holding said secondary member from movement axially or rotatably when said restraining means is released.

4. An internal casing wrench comprising: a primary member, having a cam; means for moving said primary member into a casing and for holding same stationary; a secondary member carried by said primary member, said secondary member being movable in an axial direction on said primary member; a projection formed on one of said members adapted to engage a shoulder of the other of

said members for restraining said members from relative axial movement, one of said members having a slot with which said projection may be aligned to permit a relative axial movement between said members; jaws carried by said secondary member, said jaws being engaged by said cam and moved into engagement with said casing when a relative axial movement between said primary and secondary members occurs; and means carried by said secondary member for engaging said casing and frictionally holding said secondary member from movement axially or rotatably when said projection is aligned with said slot so that said relative movement between said primary and secondary members occurs.

5. An internal casing wrench comprising: a primary member, having a cam; means for moving said primary member into a casing and for holding same stationary; a secondary member carried by said primary member, said secondary member being movable in an axial direction on said primary member; a projection formed on one of said members adapted to engage a shoulder of the other of said members for restraining said members from relative axial movement, one of said members having a slot with which said projection may be aligned to permit a relative axial movement between said members; jaws carried by said secondary member, said jaws being engaged by said cam and moved into engagement with said casing when a relative axial movement between said primary and secondary members occurs; means yieldably holding said jaws in retracted position; and means carried by said secondary member for engaging said casing and frictionally holding said secondary member from movement axially or rotatably when said projection is aligned with said slot so that said relative movement between said primary and secondary members occurs.

6. An internal casing wrench comprising: a primary member, having a cam; means for moving said primary member into a casing and for holding same stationary; a secondary member carried by said primary member, said secondary member being movable in an axial direction; a projection formed on one of said members adapted to engage a shoulder of the other of said members for restraining said members from relative axial movement, one of said members having a slot with which said projection may be aligned to permit a relative axial movement between said members, said slot being wider than said projection so that said members may rotate relatively after said relative axial movement occurs; jaws carried by said secondary member, said jaws being engaged by said cam and moved into engagement with said casing when a relative axial movement between said primary and secondary members occurs, said jaws being moved into tighter engagement with said casing by

- said cam when a relative rotative movement occurs between said primary and secondary members; and means carried by said secondary member for engaging said casing and frictionally holding said secondary member from movement when said projection is aligned with said slot so that said relative movement between said primary and secondary members occurs.
- 10 7. An internal casing wrench comprising: a primary member, having a cam; means for moving said primary member into a casing and for holding same stationary; a secondary member carried by said primary member, said secondary member being movable in an axial direction on said primary member; a projection formed on one of said members adapted to engage a shoulder of the other of said members for restraining said members from relative axial movement, one of said members having a slot with which said projection may be aligned to permit a relative axial movement between said members, said slot being wider than said projection so that said members may rotate relatively after said relative axial movement occurs; jaws carried by said secondary member, said jaws being engaged by said cam and moved into engagement with said casing when a relative axial movement between said primary and secondary members occurs, said jaws being moved into tighter engagement with said casing by said cam when a relative rotative movement occurs between said primary and secondary members; means yieldably holding said jaws in retracted position; and means carried by said secondary member for engaging said casing and frictionally holding said secondary member for movement when said projection is aligned with said slot so that said relative movement between said primary and secondary members occurs.
8. An internal casing wrench adapted to be lowered into a casing for gripping the inner surface thereof, said wrench comprising: a primary member adapted to be lowered into a casing; a secondary member associated with said primary member, said secondary member being movable axially and rotatably relative to said primary member; gripping means carried by said secondary member and operable to grip said casing; operating means for causing said gripping means to grip said casing upon a relative axial movement of said primary and secondary members and for causing said gripping means to more tightly grip said casing when a relative rotative movement takes place between said primary and secondary members; and limiting means for limiting the tightening effect of said means.
9. An internal casing wrench adapted to be lowered into a casing for gripping the inner surface thereof, said wrench comprising: a primary member adapted to be lowered into a casing; a secondary member associated with said primary member, said secondary member being movable axially and rotatably relative to said primary member; gripping means carried by said secondary member and operable to grip said casing; operating means for causing said gripping means to grip said casing upon a relative axial movement of said primary and secondary members and for causing said gripping means to more tightly grip said casing when a relative rotative movement takes place between said primary and secondary members; and limiting means for limiting the tightening effect of said means.
10. An internal casing wrench comprising: a primary member, having a cam; means for moving said primary member into a casing and for holding same stationary; a secondary member carried by said primary member, said secondary member being capable of rotatively moving on said primary member and being movable in an axial direction on said primary member; means for releasably restraining said primary and secondary members from relative axial movement; jaws carried by said secondary member, said jaws being engaged by said cam and moved into engagement with said casing when a relative axial movement between said primary and secondary members occurs, said jaws being moved into tighter engagement with said casing when a relative rotative movement takes place between said primary and secondary members; and limiting means for preventing said jaws from being tightened beyond a certain extent.
- In testimony whereof, I have hereunto set my hand at Los Angeles, California, this 23rd day of June, 1927.
- CHESTER A. RASMUSSEN.
